WINDER

Burt A. Peterson, Rockford, Ill., assignor to Barber-Colman Company, Rockford, Ill., a corporation of Illinois

Application February 15, 1932, Serial No. 593,064

11 Claims. (Cl. 242—39)

In certain aspects, this invention is an improvement upon the construction shown in the Colman Patent No. 1,267,977, dated May 28, 1918. That patent discloses an automatic winder comprising a large number of winding units and a winder-tending mechanism arranged to travel along the units. Means is also provided for detecting the fact that the "cheeses" being formed have attained the desired diameter. This means consists of a feeler mounted upon the traveling winder-tending mechanism in position to gage cheeses that have been "thrown out" or, i. e., placed in idle position. When the feeler engages a cheese that has reached the desired size, devices are actuated to prevent another bobbin from being tied to and wound on that cheese. However, since the feeler gages only thrown-out cheeses, yarn continues to be wound upon the running cheeses until they are thrown out, by which time in many instances they exceed the desired size. In practice, the amount of yarn contained in the cheeses varies by as much as the quantity of yarn on one complete bobbin. This variation is permissible when the cheeses are being formed of small bobbins, but when large bobbins are being used a variation of one bobbin is too great to be tolerated.

The present invention aims to insure that the cheeses shall all contain approximately the same amount of yarn. In the embodiment herein shown of the invention, this object is attained by providing individual cheese-measuring devices, one for each winding unit, said devices becoming effective to prevent the further winding of yarn upon the cheeses as soon as the cheeses have reached a predetermined diameter.

In the accompanying drawings,

Figure 1 is a fragmental side elevation of a machine embodying the features of my invention. Fig. 2 is a fragmental cross-sectional view of the machine.

Fig. 3 is a detail view of the cheese-measuring device in its normal or reset position.

Fig. 4 is a similar view, but showing the cheese-measuring device after it has been tripped off by a full cheese.

Fig. 5 is a perspective view of the cheese-measuring device in its tripped-off position.

Fig. 6 is a detail view of the yarn-breaking element.

The machine which has been chosen for illustration herein is of the type fully disclosed in the before-mentioned Colman patent, but I would have it understood that the invention is not limited to use in machines of that character.

Referring to Figs. 1 and 2: The machine comprises mechanism for rewinding yarn from bobbins *a* onto tubular cores *b* to form cheeses *c*, and a mechanism *T* arranged to travel along the winding mechanism and attach the ends of the yarn on the bobbins to the ends of the yarn on the cheeses, and perform various other operations attending the production of cheeses. A number of bobbins are unwound, one after another, to produce each cheese. Each bobbin *a* is supported for the drawing of yarn off the end of the bobbin.

The winder consists of an elongated framework, portions of which are indicated at 1 and 2, said framework providing two parallel sides, each side having means for supporting bobbins and means for supporting and rotating cheeses. The winder-tending mechanism travels in a circuit upon the framework of the machine and ties the end of the yarn on a reserve bobbin to every cheese except those which have reached the desired diameter, the latter being removed from the machine prior to the arrival of the winder-tending mechanism.

The winder may be considered as consisting of a plurality of units, each unit comprising means for supporting a winding couple (i. e., a bobbin and a cheese), means for rotating the cheese and traversing the yarn, yarn guiding means *x* adjacent to the bobbin, and means for throwing the cheese out of operation upon exhaustion of the yarn. The cheeses are rotated through peripheral contact with rotary drums 3 having peripheral yarn-traversing grooves 4. Each winding unit comprises a cheese-supporting arm 5 pivoted at 6 and arranged to be swung from the running position shown at the right-hand side of Fig. 2 to the inactive position illustrated at the left-hand side of Fig. 2 by means 6 which is sensitive to the exhaustion or breaking of the yarn running from the bobbin to the cheese. For a full disclosure of such throw-out mechanism, reference may be made to the before-mentioned Colman patent.

For each winding unit there is provided a cheese-measuring device located behind and in the vertical plane of the running cheese and arranged to be engaged by the periphery of the cheese when the latter has approximately attained the desired diameter. In the present embodiment of the invention, the cheese-measuring device is in the nature of a plate 7 with the upper portion of which the periphery of the cheese comes in contact, said plate being pivoted at 8 to a bracket 9. Adjustably attached to the lower

portion of the plate 7 is a latch 10. A contractile spring 14, together with the action of gravity, normally holds the plate 7 in the position shown in Fig. 3, the latch 10 bearing against a stop portion 15 of the bracket 9, and against a portion 16 of an arm 17 which is pivoted to the bracket 9 at 18. Just forward of the portion 16 is an opening 19. Rigid with the arm 17 is a downwardly extending arm 20 to which is connected one end of a yarn-breaker rod 21. The lower end of the rod 21 extends through a guide 22 into proximity to the path of the ballooning yarn *d* that is being unwound from the bobbin *c*. Preferably, the lower end of the rod 21 is roughened as shown at 23 in Fig. 6.

When the cheese has almost reached the desired diameter, its periphery comes into contact with the plate 7, and as yarn continues to be wound upon the cheese the plate 7 is swung clockwise, as viewed in Fig. 3, until the end of the latch 10 has been moved off the portion 16 and into register with the opening 19, whereupon gravity causes the bell crank 17, 20 to swing clockwise, as viewed in said figure, thereby projecting the lower end of the rod 21 into the path of the ballooning yarn, thus causing the yarn to break. Thereupon the automatic throw-out mechanism hereinbefore referred to causes the cheese arm 5 to swing from the running position shown at the right-hand side of Fig. 2 to the idle position represented at the left-hand side of said figure.

Means is preferably provided to enable the operator to distinguish the full cheeses from thrown-out cheeses which have not quite attained the predetermined diameter. The means herein shown for this purpose comprises an indicator in the form of a sheet-metal part 24 which is mounted to slide longitudinally of the plate 7. The lower end of the indicator 24 rests at all times upon the arm 17. When the cheese-measuring device is in its normal or reset position, as shown in Fig. 3, the upper end of the indicator 24 is invisible to the operator, but when the bell crank 17, 20 moves under the action of gravity into yarn-breaking position, the indicator is lifted so that its upper end is visible above the plate 7, thus signalling to the operator that the cheese of that unit is to be removed before the winder-tending mechanism reaches it.

The yarn-breaking device 21 and the cheese-measuring device 7 may be reset by any preferred means. Herein I have shown the winder-tending mechanism as equipped with means to effect such resetting. Said means comprises a member 25 fixed to the framework of the winder-tending mechanism, said member having a cam surface 26 (Fig. 5) arranged to travel in a path which brings it into engagement with the arms 17. Upon reaching an arm 17 which is in the tripped or elevated position shown in Fig. 4, the cam surface 26 depresses said arm to the dotted line position represented in Fig. 3, thereby retracting the rod 21 and bringing the portion 16 below the latch 10. As soon as the portion 16 has been moved below the latch 10, the spring 14 draws the plate 7 against the stop 15, thus placing said plate in initial or normal position. When the member 25 travels off the arm 14, gravity places the bell crank 17, 20 in the full-line position shown in Fig. 3.

To provide for adjustment of the plate 7 to compensate for variations in the manufacture of the parts, the latch 10 is adjustably connected to the plate, as before stated. As shown

in Figs. 4 and 5, the latch lies between the plate and a web 27 struck back out of the plane of said plate. The upper end of the latch bears against a stop lug 28 on the plate 7. An adjusting screw 29 carried by the plate 7 bears against the latch at a point below the web 27. It will be seen that by adjusting the screw 29 the lower portion of the latch may be sprung a greater or less distance from the lower end of the plate 7, thus placing the upper or cheese-gaging portion of the plate 85 in the desired position.

30 is a stop on the bracket 9 to limit accidental rearward movement of the plate 7.

To facilitate changes in the size of the cheese to be wound, the cheese-measuring devices are 90 arranged in groups, each group being mounted on a bar 31 which is adjustably supported on the machine frame. In the present construction the bar 31 is secured to brackets 32 which are pivoted at 33 to the frame members 2. The brackets 32 95 are adjustably attached to the members 2 by means of the screws 34 and nuts 35. It will be seen that when the cheeses are to be made of smaller diameter the bars 31 may be adjusted by means of the screws 34 to locate the cheese-100 measuring devices farther forward, and that an increase in diameter may be obtained by adjusting the bars 31 toward the rear.

Inasmuch as individual means is provided for gaging the cheeses, it will be seen that the amount 105 of yarn wound on each cheese core *b* may be accurately controlled.

With the construction shown in the Colman patent above referred to, the operator has no indication of the fact that a cheese has reached 110 the desired diameter except the fact that the cheese is thrown out immediately after the winder-tending mechanism leaves the unit. Hence after the operator has replaced the full cheese with a cheese core *b* having a small amount 115 of "starter" yarn thereon the unit remains idle until the winder-tending mechanism returns to it. With the construction herein shown, wherein a visual signal is provided, the full cheeses may be replaced with cheese cores before the winder-120 tending mechanism arrives, thus keeping the units in operation a greater percentage of the time.

When small bobbins are being unwound the breaker rods 21 may, if desired, be omitted in 125 order to reduce the number of "tailings" bobbins, and the visual signal may be used to distinguish thrown-out full cheeses from thrown-out cheeses that have not attained the predetermined diameter.

While I have described the present embodiment of the invention in considerable detail it will be understood that the invention is not limited to such details, but that various changes may be made within the scope of the appended claims. 130

I claim as my invention:

1. A winder comprising a series of winding units, each winding unit comprising a member sensitive to the size of the yarn mass being formed in the unit, and means controlled by said sensitive 140 device for interrupting winding in the unit; and mechanism arranged to travel along the series of units for resetting said sensitive devices and the winding-interrupting means controlled thereby.

2. A winder comprising a series of winding units, each winding unit comprising means sensitive to the diameter of the yarn mass being formed in the unit, and means controlled by said sensitive means for interrupting winding in the unit; and mechanism arranged to travel along the series 145 150 of units for resetting said sensitive devices and the winding-interrupting means controlled thereby.

of units for resetting said winding-interrupting means.

3. A winding unit comprising means for supporting a winding couple, a support adjacent to the yarn mass being formed, a plate pivoted to said support to swing upon a horizontal axis and extending upwardly from said axis, said upwardly extending portion being located in position to be engaged by the periphery of said yarn mass as the latter attains the desired diameter, a member pivoted below said plate to swing upon a horizontal axis, said plate having a part which normally rests upon and restrains said member, but which is moved out of engagement with said member when the plate is swung through engagement with the growing yarn mass, a downwardly extending arm rigidly connected to said member, and a breaker rod connected to said arm and arranged to be moved into the path of the ballooning yarn of the couple to break said yarn, said arm and rod tending to gravitate into yarn-breaking position.

4. A winding unit comprising means for supporting a winding couple, a support adjacent to the yarn mass being formed, a plate pivoted to said support to swing upon a horizontal axis and extending upwardly from said axis, said upwardly extending portion being located in position to be engaged by the periphery of said yarn mass as the latter attains the desired diameter, a member pivoted below said plate to swing upon a horizontal axis, said plate having a part which normally rests upon and restrains said member, but which is moved out of engagement with said member when the plate is swung through engagement with the growing yarn mass, and means connected to said member for interrupting the winding.

5. A winding unit comprising means for supporting a winding couple, means to gage the yarn mass being formed, a yarn guide adjacent to the supply member of the winding couple to guide the yarn in its travel to the receiving member of the couple, and to cause the yarn to balloon between the supply member and said yarn guide, and a breaker member connected to said gaging means and arranged to be moved to project one end of said member into the path of the ballooning yarn of the couple to break said yarn.

6. A winding unit comprising means for supporting a winding couple, a support adjacent to the yarn mass being formed, a plate pivoted to said support to swing upon a horizontal axis

and extending upwardly from said axis, said upwardly extending portion being located in position to be engaged by the periphery of said yarn mass as the latter attains the desired diameter, a spring tending to hold said plate in initial position, a member pivoted below said plate to swing upon a horizontal axis, said plate having a part which normally rests upon and restrains said member, but which is moved out of engagement with said member when the plate is swung through engagement with the growing yarn mass, a visual indicator mounted on said plate and resting upon said member and movable into signaling position when said part is moved out of engagement with said member.

7. In a textile machine, a pivoted yarn-mass-gaging member, a plate pivoted to swing upon a horizontal axis, a member pivoted below said plate to swing upon a horizontal axis, said plate having a part which normally rests upon and restrains said member from upward movement, but which is moved out of engagement with said member when the plate is swung through engagement with a growing yarn mass, and an indicator slide mounted on the back of the plate and resting upon said member and movable upwardly by said member to expose the upper portion of the slide above the plate.

8. In a textile machine, a pivoted yarn-mass-gaging member, a visual indicator slidably mounted on said member, and means for causing relative sliding movement between the gaging member and the indicator, said means being normally restrained by said gaging member.

9. In a textile machine, a yarn-mass-gaging member, an indicator movably supported behind said member, and means for causing relative movement between said member and said indicator to move a portion of the latter out from behind the gaging member.

10. In a textile machine, a yarn-mass-gaging member, an indicator movably mounted on the rear side of said member, and means for causing a portion of the indicator to be moved out from behind the gaging member to expose said portion to view.

11. In a textile machine, a yarn-mass-gaging member, an indicator normally hidden by said member, and means whereby movement of the gaging member exposes the indicator to view.
